UNITED STATES PATENT OFFICE.

JOSEPH DERK, OF PHILADELPHIA, PENNSYLVANIA.

DESIGN FOR A SCARF.

Application filed May 3, 1926. Serial No. 17,546. Term of patent 3½ years.

To all whom it may concern:

Be it known that I, JOSEPH DERK, a citizen of the United States, residing in the city and county of Philadelphia, State of Pennsylvania, have invented a new, original, and ornamental Design for Scarf, of which the following is a specification, reference being had to the accompanying drawing, forming part thereof. The drawing illustrates a trifle more than one-half of the scarf, and

the two horizontal panels shown at the upper part of the figure of the drawing are duplicated below the substantially circular panel in the center of the scarf.

The figure is a plan view of a scarf, showing my new design.

I claim:—

The ornamental design for a scarf, as shown and described.

JOSEPH DERK.
